BAG LOCK.

Application filed December 8, 1927. Serial No. 238,480.

Our invention relates to improvements in bag locks and has for its object to provide a bag lock having a key which cannot be easily removed from the lock when the bag is closed and the key is in normal position. It further has for its object to provide means by which the key can be manually projected when the bag is open so as to be easily removable. It further has for its object to provide means for yieldingly holding the key in partially expelled position. It further has for its object to provide means for rendering the lock difficult to pick. It further has for its object to provide a lock having a key which may be left in place without producing an objectionable appearance.

The following is a description of our invention reference being had to the accompanying drawings, in which:

Figure 1 shows a portion of a bag partially broken away to which a lock embodying our invention is affixed;

Fig. 2 is a section of the lock and bag frame on the lines 2—2, Figs. 1 and 3;

Fig. 3 is a longitudinal section on the line 3—3, Fig. 2;

Fig. 4 is a horizontal section on the line 4—4, Fig. 3;

Fig. 5 is a section on the line 5—5, Fig. 3 with the key shown in partially expelled position;

Fig. 6 shows a detail, being a plan view of a portion of the lock with the key removed.

Referring more particularly to the drawings, 2 represents a traveling bag having the usual frame (not shown) to which is affixed a lock 4 embodying our invention. This lock embodies a lock casing 6 of ordinary construction having on its upper face plate a hollow projection 8 and containing guide posts 10 surrounded by springs 12 which tend to move the catch plate 14 toward holding position. This catch plate is provided with the ordinary catches 16 to engage the loop member 18 in the ordinary manner. The upper face of the projection 8 is provided with a slot 20, preferably a zigzag slot, which is adapted to receive a key 22, and conforming to the slot and corrugated when the slot is a zigzag slot. This key is provided with an enlarged head 24, the lower edge of which is normally housed within a recess 26 on the upper face of the projection 8. This recess

is of sufficient depth to substantially receive the enlarged head 24 when the same is in its lowermost position.

The catch plate 14 is provided with a central longitudinal opening 28 having at its end downwardly extending tangs 30 with which shoulders 32 upon the key engage, the key itself being of sufficient length to extend below the tangs 30, as shown in Fig. 3.

When the key is fully in place pressure on the head thereof forces the same downward and forces the catch-plate downward until the catches 16 are released from the loops 18. When in normal position as shown in Fig. 3 the head 24 of the key does not project sufficiently above the top of the projection 8 to be easily grasped by the hand or to be objectionable either as a projection or as an unsightly element. Because it is not objectionable in appearance, when in normal position, it can be left in place at all times except when it is desired to remove it so as to prevent the operation of the lock. Furthermore, since it does not, when in normal position, project so as to be easily grasped it cannot be removed except by a considerable effort, unless partially expelled in the manner hereinafter described.

In order to provide means for making the key easily removable we mount upon one of the side walls of the casing a lever 34 pivoted at 36 and having a thumb-piece 38 extending through a slot in the casing and a portion 40 which when the lever is actuated moves into the path of the key 22 so as to partially expel the same into a position where it can be easily grasped by the hand and removed. The finger-piece 38, extending through a portion of the lock case which is within the bag when the bag is closed, is accessible only when the bag is open. In order to remove the key, the key is first pressed so as to permit the bag to be opened, and then when the bag is open the lever 34 is manipulated so that the portion 40 expels the key to the positions shown in dotted lines in Fig. 3. The key is then easily grasped and removed. The key is provided with a hole 39 so that it can when removed be placed upon a key ring.

If it is desired to lock the bag, the lever 34 is manipulated so as to expel the key and the key is then removed whereupon the bag is closed and is thus locked, the lock being as difficult to pick as most bag locks at pres-

ent in use. In order to increase the difficulty in picking the lock, the tangs 30 with downwardly sloping upper surfaces are provided so that if a wire is passed through the slot 5 so as to engage the catch-plate it will tend to slip off the tangs and pass through the hole 28.

In order to frictionally hold the key in place we provide a spring member 42 consisting of a yoke secured to the catch-plate by tangs 44 having spring leaves 46 which yieldingly engage the sides of the key. These spring members are inclined and also act as guides for a wire or other instrument 15 which might be introduced through the slot 20 guiding it so that it passes through the openings 28 instead of engaging the edges thereof.

48 is the ordinary escutcheon for the lock 20 surrounding the projection 8.

With the lock above described, the key may be left in the lock at all times without detracting from its appearance and when it is desired to leave the bag in locked condition this can be accomplished by simply removing the key and closing the bag, and, furthermore, when the bag is closed and the key is in position the key cannot be easily removed without first opening the bag. The 30 liability that any one will intentionally remove the key for the purpose of making trouble is, therefore, minimized since such removal would require such manipulation as would be likely to attract attention if 35 performed by an unauthorized person.

As will be evident to those skilled in the art, our invention permits various modifications without departing from the spirit thereof or the scope of the appended claims.

49 What we claim is:

1. In a bag lock a casing, lock mechanism within the casing adapted to be controlled by a removable non-rotating key controlling said lock mechanism, and manually controlled means having a portion within the casing movable in the path of the key to partially expel said key from said casing so that it protrudes sufficiently to be easily grasped for removal.

50 2. In a bag lock a casing, lock mechanism within the casing adapted to be controlled by a removable non-rotating key controlling said lock mechanism, and manually controlled means having a portion within the casing movable in the path of the key to partially expel said key from said casing so that it protrudes sufficiently to be easily grasped for removal, and spring means adapted to engage said key while so expelled.

55 3. In a bag lock a casing, lock mechanism comprising a spring actuated catch plate within said casing adapted to be controlled by a removable push key extending through the upper face of said casing and below said

the upper surface of said catch plate, and manually controlled means having a portion below said catch plate and movable in the path of said key for partially expelling said key from said casing so that it protrudes 70 sufficiently to be easily grasped for removal.

4. In a bag lock a casing, lock mechanism comprising a spring actuated catch plate within said casing adapted to be controlled by a removable push key extending through the upper face of said casing and below said 75 catch plate and having a portion engaging the upper surface of said catch plate, and manually controlled means having a portion below said catch plate and movable in the path of said key for partially expelling said key from said casing so that it protrudes 80 sufficiently to be easily grasped for removal and spring means engaging said key while so expelled.

5. In a bag lock a casing, lock mechanism comprising a spring actuated catch plate within said casing having an opening with downwardly sloping end surfaces, said catch plate being adapted to be controlled by a removable push key extending through the upper face of said casing and below said catch plate and having portions engaging said downward surfaces of said catch plate and manually controlled means having a 95 portion below said catch plate and movable in the path of said key for partially expelling said key from said casing so that it protrudes sufficiently to be easily grasped for removal.

6. In a bag lock a casing, lock mechanism comprising a spring actuated catch plate within said casing adapted to be controlled by a removable push key extending through the upper face of said casing and below said 105 catch plate and having a portion engaging the upper surface of said catch plate and a manually operable lever pivotally mounted on said casing and having a portion below said catch plate and movable in the path of said key for partially expelling said key from said casing so that it protrudes sufficiently to be easily grasped for removal.

7. In a bag lock a casing, lock mechanism comprising a spring actuated catch plate within said casing adapted to be controlled by a removable push key extending through the upper face of said casing and below said catch plate and having a portion engaging the upper surface of said catch plate and a manually operable lever pivotally mounted on said casing and having a portion below said catch plate and movable in the path of said key for partially expelling said key from said casing so that it protrudes sufficiently to be easily grasped for removal, said lever having its power arm positioned so as to be within the bag to which the lock is applied.

8. In a bag lock a casing, guide posts

within said casing, a catch plate mounted on said guide posts, springs on said guide posts tending to move said plate to holding position, said catch plate being adapted to be controlled by a removable push key having a portion extending through the top of said casing and below said catch plate and a portion engaging the top surface of said catch plate and a manually operable lever pivoted to said casing and having a portion adapted to engage the lower end of said key and partially expel said key from said casing so that it protrudes sufficiently to be easily grasped for removal and spring means engaging said key while so expelled.

9. In a bag lock a casing, lock mechanism within the casing adapted to be controlled by a removable non-rotating key controlling said lock mechanism, and manually controlled means having a portion within the casing movable in the path of the key to partially expel said key from said casing so that it protrudes sufficiently to be easily grasped for removal, said plate having a recess surrounding the head of said key so that normally it can not be easily grasped manually for removal.

10. In a bag lock a casing, lock mechanism within the casing adapted to be controlled by a removable non-rotating key controlling said lock mechanism, and manually controlled means having a portion within the casing movable in the path of the key to partially expel said key from said casing so that it protrudes sufficiently to be easily grasped for removal, said upper face of said casing having a recess surrounding the head

of the key when said key is in its innermost position.

11. In a bag lock a casing, lock mechanism comprising a spring actuated catch plate within the casing adapted to be controlled by a removable non-rotating key controlling said lock mechanism and manually controlled means having a portion within the casing movable in the path of the key to partially expel said key from said casing so that it protrudes sufficiently to be easily grasped for removal, said upper face of said casing having a recess surrounding the head of the key when said key is in normal position.

12. In a bag lock a casing, lock mechanism comprising a spring actuated catch plate within the casing adapted to be controlled by a removable non-rotating key controlling said lock mechanism, and manually controlled means having a portion within the casing movable in the path of the key to partially expel said key from said casing so that it protrudes sufficiently to be easily grasped for removal, said upper face of said casing having a recess surrounding the head of the key when said key is in its normal position, said catch plate having an elongated slot through which said key protrudes and downwardly sloping portions at the ends of said slot constituting the portions engaged by said key.

In testimony whereof, we have signed our names to this specification this 6th day of Dec., 1927.

JOHN B. RUSS.
CLARENCE E. SMITH.
